UNITED STATES PATENT OFFICE.

LLOYD EBERHART, OF MILWAUKEE, WISCONSIN.

COLLAR-BUTTON.

SPECIFICATION forming part of Letters Patent No. 758,742, dated May 3, 1904.

Application filed June 22, 1903. Serial No. 162,549. (No model.)

To all whom it may concern:

Be it known that I, LLOYD EBERHART, a citizen of the United States, residing at Milwaukee, in the county of Milwaukee and State of Wisconsin, have invented certain new and useful Improvements in Collar-Buttons, of which the following is a specification.

Objects of my invention are to avoid certain well-known discomforts incident to the use of collar-buttons commonly found on the market prior to my invention, to steady and avoid undesirable lateral play or tilt on the part of the stem employed as a connection between the base and head and which extends through registering buttonholes of the neckband of the shirt and the collar-band when the collar-button is in use, to adapt the collar-button to engage the neckband of the shirt in a way to oppose tendency on the part of the coat-collar of the wearer from pressing the stem toward the neck and through the buttonholes to an extent to cause the base to objectionably bind against the user's neck, and to provide a simple and efficient construction.

In the accompanying drawings, Figure 1 shows in perspective a portion of the neckband of a shirt adapted, for example, to open at the back with my improved collar button or fastener applied. Fig. 2 shows the collar button or fastener in perspective on a larger scale. Fig. 3 is an edge view of the collar button or fastener and illustrates in dotted lines the lapping portion of the neckband and a portion of the collar all buttoned together by my improved device. Fig. 4 is a vertical section, on a larger scale, through the rear portion of a shirt and collar with my improved button applied. Fig. 5 illustrates my improved collar-button formed by a bent-wire frame.

The collar-button illustrated in the first four figures of the drawings comprises a base 3, a head 6, and a stem 4, arranged between the base and head and permanently and rigidly connecting them together to form a button portion for buttoning together the neckband of a shirt and the band of a collar. The base 3 is also provided with a hooked extension comprising the hook-shank 1 and the bill 2, respectively, at opposite sides of the hook-

bend 1', the hook being arranged so that its bill 2 extends toward the head 6—that is to say, the bill is arranged in a plane between the planes of the head 6 and base 3 and preferably parallel therewith. As a simple and desirable construction, the button thus shown in the first four figures is formed of an oblong plate having a bend 1' to form the hook, a bend 3' to position the stem 4 lateral to the plane of the base 3, and a bend 5 to position 60 the head 6 at right angles to the plane of the stem.

The stem 4 is of a length to extend through the neckband, and the hook is adapted to receive the neckband portion above the button 65 hole or holes thereof through which the stem extends. The shank 4 is rendered integral with the base and head to provide a simple construction which avoids the annoyance and difficulties attending the use of buttons having hinged or detachable heads. This permanence of union between the head and base also permits my improved button to be economically manufactured and, if desired, struck up from a single metal plate.

The application of the button thus described is best shown in Fig. 4, in which it will be seen that the hook clasps opposite sides of the neckband; also, that the base 3 and its upward extension lie flatwise against the inner 80 side of the neckband, with the stem 4 extending through registering buttonholes of the neckband and collar-band and with the head 6 flatwise against the outer side of the collar-band. As illustrated, the upper portion of 85 the neckband fills the space between the two sides of the hook formed by the shank 1 and the bill 2, while the portion of the collar-band above the buttonhole therein is between the planes of the bill 2 and the head 6 and against 90 the outer side of the bill.

As a matter of further improvement, the head, base, and stem are of substantially uniform cross-sections throughout, whereby turning of the button is further avoided, it 95 being observed, however, that by making the hook of similar or sufficient width in cross-section its engagement with the upper edge of the neckband will prevent the button from twisting or laterally rocking when in use.

100

As a matter of further improvement, the head 6 is provided with an upward extension 8, which in use engages the outer side of the collar-band, as shown.

- 5 In place of forming the button of a plate I can suitably bend a wire frame, as in Fig. 5, which shows a button thus composed of a wire frame, but otherwise corresponding with the button shown in preceding figures—that is to say, the frame shown in Fig. 5 is bent to form the head 66, the stem 44, the base 33, and a hooked extension comprising the shank 11, the bill 22, and the bend 11' between the shank and bill.
- 10 15 The button herein shown can be used at either the front or back of a shirt, as may be desired. When in use, the base 3 and its upward extension will not present to the user's neck any objectionable projection, and the 20 button as a whole will be held against undesirable tilt.

What I claim as my invention is—

1. A collar-button, comprising a head, a base, a stem connecting the same and integral therewith, and a hooked extension on said base, the bill of the hook extending toward and terminating above the stem and lying on the same side of the base as said stem so as to clasp the neckband above the buttonhole.
- 25

2. A collar-button, comprising a head, a 30 base, a stem connecting the same and integral therewith, and a hook forming an extension of the base and having parallel bill and shank portions, the bill extending toward and terminating above the stem and lying on the same 35 side of the base as said stem so as to clasp the neckband above the buttonhole.

3. A collar-button, comprising a head, a base, a stem connecting the same and integral therewith, and a hook forming an extension 40 of the base, the bill of the hook extending toward the head and occupying a plane between the planes of the head and base.

4. A collar-button, comprising a head, a base, a stem connecting the same and integral 45 therewith, said parts being of substantially uniform cross-sections throughout, the head having an upward extension, and a hook forming an extension of the base and having a bill extending toward and terminating above the 50 stem and lying on the same side of the base as said stem so as to clasp the neckband above the buttonhole.

LLOYD EBERHART.
